United States Patent Office

Des. 193,825
Patented Oct. 9, 1962

193,825

LUGGAGE HANDLE STUD OR SIMILAR ARTICLE

Charles S. Gehrie, Montclair, N.J., assignor to Presto
Lock Co., Garfield, N.J., a limited partnership

Filed June 22, 1961, Ser. No. 65,678

Term of patent 14 years

(Cl. D87—2)

FIG. 1

FIG. 2

FIG. 1 is a perspective view of a luggage handle stud or similar article embodying my new design; and

FIG. 2 is an end view of the same.

The portions shown in broken lines are included for purposes of illustration only.

I claim:

The ornamental design for a luggage handle stud or similar article, as shown and described.
